Term of patent 14 years

Int. Cl. D6—01

U.S. Cl. D33—14

Fig. 1.

Fig. 2.

*Fig. 3.*FIGURE 1 is a perspective view of the drawer cocktail table of our new design, a view from a substantially diagonally opposite perspective would be substantially the same in appearance;

FIGURE 2 is a right end elevation view of the drawer cocktail table, a left end elevation view would appear as a mirror image replica thereof; and

We claim:

The ornamental design for a drawer cocktail table or similar article, as shown and described.
